LISTING ADDING MACHINE

George C. Chase, South Orange, N. J., assignor to
 Monroe Calculating Machine Company,
 Orange, N. J., a corporation of Delaware

Application August 30, 1940, Serial No. 354,786

12 Claims. (Cl. 235—60)

The invention relates to adding or adding and listing machines, and more particularly to total taking mechanism therefor.

In taking a total from accumulators equipped with crawl tens transfer gearing it has been customary to rotate the accumulator wheels successively to zero, beginning with the right hand or lower order wheel. One object of this was to subtract any partial tens transfer from a wheel before attempting to adjust a stop into the path of movement of the zero stop on the wheel, since there is no practical way to distinguish between a wheel standing at 0 registering position and one at 9.9, as would be necessary in adjusting the stop into position at one side or the other of the zero stop. Also, the successive zeroizing eliminated certain cramping actions set up in the tens transfer gearing by the spring driven actuator segments.

According to the present invention the accumulator wheels (equipped with crawl tens transfer gearing) are rotated simultaneously to zero in total taking, the first stated objection being overcome by the provision of preliminary aligning means, whereby the wheels are rotated to counteract any excessive partial tens transfer in the accumulator. The cramping action is eliminated by the omission of the actuator segment springs, the actuators being positively driven.

The invention consists in the novel construction and combination of parts, as set forth in the appended claims.

In the accompanying drawings, illustrating the invention,

Fig. 1 is a right side elevation of the value entering, differential actuator and accumulating means of an adding machine constructed in accordance with the invention.

Fig. 2 is a front elevation of parts seen in Fig. 1.

Fig. 3 is a detail right side elevation of the differential actuator drive.

Fig. 4 is a right side elevation of the total and subtotal initiating devices.

Fig. 5 is a detail right side elevation of parts shown in Fig. 1, in positions taken during alignment of an accumulator.

Fig. 6 is an exploded perspective view of the aligning or crawl transfer counteracting devices.

In these drawings the invention is shown as applied to an adding-listing machine similar to that disclosed in United States Patent No. 1,867,002, issued to Clyde Gardner on July 12, 1932, and employing the crawl tens transfer means of

United States Patent No. 1,828,180, issued to Clyde Gardner on October 20, 1931. The positive actuation means employed is of the general type disclosed in United States Patent No. 1,202,800, issued to Thomas Carroll on October 31, 1916. The machine may be hand operated, as in the above noted patents, or it may be operated by an electric motor, as disclosed in United States Patent No. 1,932,013, issued to Loring P. Crosman on October 24, 1933.

Accumulation

Amounts set up in the keyboard 215 are registered in one or more accumulators 473 and are set up in the type bars 611 by means of differential actuators consisting in each denominational order of two levers 610 and 500 (Figs. 1 and 2) having toothed segments engaging opposite sides of a pinion 501.

Each lever 610 is provided with a toothed segment with which the pinions 472 of any one or more of a series of accumulators 473 may be engaged, by movement of the accumulator shafts 403. Each lever 610 is also connected with a type bar 611, and with a stop bar 615 cooperating with the stem of a depressed key 215 to limit the movement imparted to the accumulators and type bar, in accordance with the key value. Each lever 500 is connected with a stop bar 502 which also cooperates with the stem of a depressed key 215 in effecting the desired accumulation. Depression of a key 215 will lift the related column latch 214 out of the path of a stop of bar 615, in known manner, the column latches preventing operation of the levers 610 in columns in which no key is depressed.

The pinions 501 are mounted on a shaft 503, which shaft is oscillated during the operation of the machine to give the pinions a fixed degree of oscillatory movement. Shaft 503 is mounted in a frame 616 (Fig. 3) pivoted upon the supporting shaft 608 of the levers 610, 500. Frame 616 is provided with rollers 504 engaging cam slots of a pair of plates 318 (one of which is shown in the drawings) fixed upon a rock shaft 301.

In the operation of the machine shaft 301 is rocked, either by means of a hand lever or by power connections, thereby, through cam plate 318, oscillating shaft 503 about point 608. During the forward stroke of cam plate 318 the levers 610 and 500 will be carried counter-clockwise with the pinions 501 until the teeth of stop bars 615 and 502 contact with the stem of the depressed key. The teeth of these bars are so

arranged with relation to the key stems that the levers 610 and 500 will be complementally operated, the levers 610 being given a movement corresponding to the value of the depressed key and the lever 500 being given a movement corresponding to the full rearward movement of pinion 501, less the movement of lever 610. The full movement imparted by pinion 501 is somewhat greater than the movement of lever 610 in registering the digit 9, this extra movement being provided for in bar 502, which is given a slightly longer movement in engaging each of the key stems. The purpose of this extra movement will be explained later. In the return stroke of plates 318, levers 610 and 500 will be moved reversely, against appropriate stops, which will be described in connection with the total taking mechanism.

As is well known in machines of the present type, and described in Patent No. 1,867,002, hereinbefore referred to, addition is performed on a given accumulator by holding the same disengaged from the actuator segments during the first described stroke of the parts, and by engaging the accumulator with said segments and holding it in engagement during the return stroke. Similarly, subtraction is effected by engaging the accumulator with the segments and holding it engaged during the first stroke and by maintaining it disengaged from the segments during the return stroke.

Total taking

A total registered on an accumulator 413 is set up in the type bars 611 and printed according to the well known method. That is to say, the accumulator is engaged with the actuator segments, the column latches 214 are all released and the accumulator wheels are rotated subtractively to zero, thus setting the accumulated value in the type bars 611, wherefrom it is printed. The accumulator is disengaged during the return stroke, as in subtractive operations. Sub-totals are taken in the same manner, except that the accumulators are maintained in engagement with the actuator segments during both strokes of the operating mechanism, whereby the total, which has been subtracted from the accumulator wheels, is added back into the accumulator after the printing has been effected.

The total key 273 and the sub-total key 278 (Fig. 4) set the accumulator control devices for the appropriate operation, in the manner set forth in Patent No. 1,687,002, and also effect rocking of a bail 281, thereby releasing the column latches. Each of these keys is also provided with a forward extension overlying a pin fixed in the upper end of a spring retracted slide 505, this slide having at its lower end a shoulder adapted to engage a pin fixed in a crank arm 506 of total setting shaft 507. Lost motion is provided between this pin and shoulder, in order that the column latches will be released before shaft 507 is rocked. Shaft 507 is provided with a series of cam arms 508 (Fig. 1) adapted, in the depression of the total or sub-total key, to act successively upon the arms 508, one of which arms is related to each differential actuator column. In order to insure that all of the cam arms 508 are effectively operated the total and sub-total keys will remain unlatched until the key stroke is completed, at which time latch 283 will become effective to lock the operated key in fully depressed position. Upon the free

end of each arm 508 is pivoted a link 510 having a stud engaging the diverging slots of a pair of levers 511, 512. A spring 513 normally holds the rear end of link 510 raised, maintaining contact of lever 512 with a fixed stop 514. In the normal position of the parts the slot of lever 512 extends in the direct line of movement of the stud of link 510, while the slot of lever 511 is so disposed that forward movement of link 510 will induce clockwise movement of said lever, as viewed in Fig. 1. Lever 511 has pivotal connection with an adjustable totaling stop 613, having guiding support upon the shaft 608, and provided with projections related respectively to the different accumulators.

An accumulator 413 being moved into engagement with the actuator segments, and the total or sub-total key depressed, the series of totaling stops 613 will be moved forwardly by levers 511, 20 each into contact with one of a series of control disks 515, fast upon the wheels of the accumulator. Each of the disks 515 is provided with a notch, standing opposite the tooth of the stop 613 when the related accumulator wheel stands in the zero registering position, one wall of this notch being extended radially to form a zero stop 457. Preferably the periphery of disk 515 is formed as a small cam, having a uniform drop from the high point of the zero stop to the low point at the intersection with the other wall of the notch.

As stated, the accumulator wheels are provided with tens transfer mechanism of the crawl type—that is to say, each lower order wheel is connected with the next adjacent higher order wheel by ten-to-one ratio gearing. Assuming that a given accumulator wheel stands at 9 and that the next adjacent lower order wheel stands at 8 or 9, it will be obvious that the actual position of the higher wheel will be 9.8 or 9.9, which is substantially the 0 position of the wheel. Therefore, as so far described, the tooth of stop 613 might engage the notch of the higher order cam disk 515 before the accumulator is rotated in which case the accumulator wheel, the lever 610 and the type bar 611 would all remain at zero when shaft 301 is operated. Such an action might be permissible if positive zero setting of the accumulator wheels were the only requirement, but would result in an error in operations of total taking, wherein the levers 610 of the several orders must move in accordance with the numerical total registered by the accumulator wheels.

The levers 512 are intended to prevent this erroneous operation, by counteracting the fractional tens transfer registration in the higher order accumulator wheel. The slotted connection of levers 511 and 512 with link 510 provides for complemental movement of the levers upon depression of the total key. If lever 511 is free to move, spring 513 will hold lever 512 in its normal position and lever 511 will be rotated clockwise. If, on the other hand, lever 511 is held, lever 512 will be rotated counter-clockwise. If the movement of lever 511 becomes obstructed at any instant during the forward movement of link 510, the remaining movement of the link will effect a corresponding counter-clockwise movement of lever 512. It will be noted that when the zero stop of a higher order wheel is in position to be erroneously engaged by stop 613, the lower order wheel will stand at 9, 8 or possibly 7, and that consequently the totaling stop 613 in this lower order will be prevented from making

any considerable movement toward the center of the cam disk 515. Therefore, lever 511 being prevented from making any substantial movement, in response to the movement of link 510, the stud of said link will cam along the slot of lever 511 and will thereby displace lever 512 counter-clockwise, as viewed in Fig. 1. This will bring lever 512 into contact with a pin 516, fixed in the actuator segment of the higher order actuator lever 610, advancing the segment and thereby rotating the higher order accumulator wheel far enough in a subtractive direction so that the tooth of stop 613 cannot erroneously enter the notch of the related cam disk 515. Obviously, a portion only of the fractional transfer registration need be counteracted, in order to allow the stop 613 to engage properly on top of the zero stop tooth 457. For example, if the four wheels of lowest order register a total of 9999, these four wheels would stand at 9.999, 9.99, 9.9 and 9, from left to right respectively, before the total or sub-total key is depressed, and it will be sufficient if the tens, hundreds and thousands wheels are each successively retracted to approximately 9.5 during the depression of the total or the sub-total key.

Normally, the differential actuators of the machine stand locked, because of the normal position stops 514 and 517 and the known locating means for the driving elements. In zeroizing the accumulator wheels it is necessary to the elimination of the partial tens transfer values, either by preliminary alignment or during the zeroizing action proper, that the differential actuator lever 610 and the complementally operated levers 500 be operated in opposite directions, from normal position. Hence, it is necessary, in zero setting operations, to disable at least one of the normal position stops, allowing an abnormal movement of the related lever. If the tooth of stop 613 were allowed to enter the notch of a wheel standing at 9.9, it would be necessary to free lever 610 so that it could make .8 or .9 of a step of abnormal (clockwise) movement during the zero setting operation.

In the present construction fractional advance of the actuator lever 610 will rotate pinion 501 and thereby effect a corresponding retraction of the related actuator lever 500, since shaft 503 is held stationary. To allow for this movement, the normal position stop of each lever 500, except the lever in the units order, is formed as a lug 517 on an extension of the lower order lever 512, so that as lever 512 is displaced counter-clockwise through the controlling action of the lower order cam disk 515 the higher order lever 500 will be permitted a short abnormal (clockwise) movement. There is, of course, no occasion for lever 500 of the units order to make this clockwise movement from its normal position, so this lever is provided with the usual fixed normal position stop.

The accumulator controls having been set for a totaling operation and the totaling stops 613 engaged with the cam disks 515, by the depression of the total or the sub-total key, shaft 301 will be oscillated and the printing effected in the usual manner. The operation may be effected by hand or by motor operation, controlled through the total or sub-total key in known manner.

During the first stroke of this operation the actuator levers 500 are to be held locked against counter-clockwise movement until the related accumulator wheels have been rotated subtractively

to zero, whereupon the totaling stops 613 will prevent further movement of actuator levers 610, and the levers 500 will be released so that they may operate during the remainder of the stroke.

5 The locking of levers 500 is effected by the extensions of levers 512, which are provided with lugs 518, each lying normally out of the path of movement of a shoulder 519 of the related actuator lever 500. As previously explained, a lever 512 remains in its normal position after the depression of the total or sub-total key only if the related cam disk 515 stands in its zero position. Whenever lever 512 is moved out of its normal position, which is whenever its related cam disk does not stand at zero, lug 518 will lie in the path of shoulder 519 so that lever 500 will not be released for free counter-clockwise movement until cam disk 515 has been restored to its zero position.

20 Theoretically shoulder 519 would extend radially with respect to shaft 608, so that, as the related accumulator wheel is rotated toward zero, lever 512 would hold actuator lever 500 against counter-clockwise movement beyond normal position until the totaling stop 613 falls into the zero notch of the cam disk. However, it is desired to effect the release of actuator lever 500 positively, rather than to rely upon spring 513 to pull the totaling stop 613 into the zero notch in effecting the release. Therefore, shoulder 519 is set at an angle, providing for a camming effect upon lever 512 during the movement of shaft 503.

25 As a result of this action, the tendency of spring 513 to swing levers 511 and 510 in a counter-clockwise direction maintaining the related totaling stop 613 against the cam disk 515 is supplemented by the tendency of shoulder 519 to urge lug 518 forwardly, which urge becomes 30 a positive driving force when the cam disk 515 is arrested in its zero position by the abutment of the zero stop tooth 457 with the related tooth of the totaling stop 613, arresting further counter-clockwise movement of lever 610 and consequently positively driving the tooth of the totaling stop into the notch of cam disk 515. As 35 shoulder 519 drives lug 518 forwardly, lever 500 may move a short distance beyond its normal position in a counter-clockwise direction before the cam disk 515 of the related numeral wheel has reached zero position, thus diverting a certain amount of movement of shaft 503 from actuator lever 610. Therefore, as previously stated, the total movement of shaft 503 must 40 be somewhat more than nine steps.

45 It may be noted that while each pair of levers 511 and 512 are complementally moved during the depression of the total or sub-total key as above described, they act in unison during the 50 rotation of the accumulator wheels toward zero, the two levers of each pair being in effect one rigid member at that time.

55 Since the totaling stops 613 engage the notches of cam disks 515 when the accumulator wheels stand at zero at the end of the forward stroke of the parts, it is necessary to remove said stops before the return stroke of the drive, so that there shall be no interference with the movement of the accumulator wheels in sub-totaling 60 and in other similar operations. The release of totaling stops 613 is effected by a cam 167 (Fig. 4) mounted on an arm 316 of rock shaft 301. Cam 167 engages a roller mounted on an arm 165 which is normally spring held in a centralized position. During the forward stroke 65

of the drive arm 185 will be rocked clockwise, as seen in Fig. 4, while in the return stroke the arm will be rocked counter-clockwise, beyond its normal position, bringing a pin 520 into contact with the slide 505 and rocking said slide about its support 521 to disengage the shoulder of the slide from the pin of crank arm 506. This will allow spring 522 (Fig. 1) to rock the cam arms 508 to normal position, permitting springs 513 to move the links 510 rearwardly and return the levers 511 and totaling stops 613 to normal position.

The relation of levers 511 and 512 to the parts with which they function may be summarized as follows: Stop 613 slides forwardly against cam disk 515. Levers 511 and 512 lie between stop 613 and the actuating levers 500, 610 of the same order. Lug 518 of lever 512 acts on lever 500 of that same order, and lug 517 crosses over stop 613 of the related order and lever 610 of next higher order, and acts on lever 500 of that higher order. Pin 516 is mounted on the right hand side of lever 610 of the higher order, passes under lever 511, and is acted on by lever 512.

The latch 263 is released in well-known manner during the return movement of the operating mechanism, permitting the total or sub-total key to resume its normal position.

While the above described mechanism has been set forth as a device for taking a total or a sub-total in a listing machine, it is apparent that it is also usable as a zero setting device for a register equipped with a tens transfer mechanism of the "crawl" type in a non-listing adding or calculating machine.

Alignment

It may be noted that if the column latches 214 are lifted and shaft 507 is rocked, against the tension of springs 522, independently of the depression of the total or sub-total keys, any partial tens transfers in the engaged accumulator will be neutralized. This would be useful in case the accumulator wheels were provided with visible digit characters, since these characters would thereby be brought into reading alignment. Upon release of shaft 507, springs 522 would cause lugs 517 to cam the levers 500 back to normal position and restore the accumulator to crawl transfer condition. Such an arrangement would call for a setting back of the higher order wheel a full tenth of a step for each unit registered in the lower order wheel (for instance from 9.9 to 9 registering position). This, of course, would involve merely the correct proportioning of cam disk 515, and would not affect the proper operation of the parts in total making.

I claim:

1. In an adding machine, the combination with an accumulator comprising wheels provided with zero stops and crawl tens transfer gearing between said wheels, differential actuators including each a power element and primary and secondary elements complementally driven thereby, each primary element having operating connection with an accumulator wheel, and driving means adapted to operate all of the power elements simultaneously; of means cooperating with the accumulator, actuators and driving means to take a total, including totaling stops adjustable into the paths of movement of the zero stops, devices operable to rotate said wheels to counteract partial tens transfers in the accumulator, and elements adjustable by said de-

vices to control the extent of movement of the secondary actuator elements during operation of the driving means.

2. In an adding machine, the combination with an accumulator comprising wheels provided with zero stops and crawl tens transfer gearing between said wheels, differential actuators including each a power element and primary and secondary elements complementally driven thereby, each primary element having operating connection with an accumulator wheel, and driving means adapted to operate all of the power elements simultaneously; of means cooperating with the accumulator, actuators and driving means to take a total, including a total key, totaling stops yieldably adjustable into the paths of movement of the zero stops, devices controlled by the total key and operable to adjust said stops, cooperating members controlled by the total key and operable upon interruption of said adjustment by engagement of any totaling stops with the peripheral faces of the related zero stops to move said primary elements to counteract partial tens transfers in the accumulator, and elements adjustable by said member to control the extent of movement of the secondary actuator elements during operation of the driving means.

3. In an adding machine, the combination with an accumulator comprising wheels provided with zero stops and crawl tens transfer gearing between said wheels, differential actuators including each a power element and primary and secondary elements complementally driven thereby, each primary element having operating connection with an accumulator wheel, and driving means adapted to operate all of the power elements simultaneously; of means cooperating with the accumulator, actuators and driving means to take a total, including totaling stops adjustable into the paths of movement of the zero stops, devices operable to rotate said wheels to counteract partial tens transfers in the accumulator, and means cooperating with said devices, to lock the secondary actuator elements against operation by the driving means, said locking means being adapted to release each secondary actuator element upon contact of the related zero stop with its totaling stop.

4. In an adding machine, the combination with an accumulator comprising wheels provided with zero stops and crawl tens transfer gearing between said wheels, differential actuators including each a power element and primary and secondary elements complementally driven thereby, each primary element having operating connection with an accumulator wheel, and driving means adapted to operate all of the power elements simultaneously; of means cooperating with the accumulator, actuators, and driving means to take a total, including a total key, totaling stops yieldably adjustable into the paths of movement of the zero stops, devices controlled by the total key and operable to adjust the totaling stops and cooperating members controlled by the total key and operable upon interruption of said adjustment by engagement of any totaling stops with the peripheral faces of the related zero stops to move said primary elements to counteract partial tens transfers in the accumulator, and means including extensions of said members cooperating with said devices to lock the secondary elements against operation by the driving means and to release each secondary actuator element upon contact of the related zero stop with its totaling stop.

5. In an adding machine, the combination with an accumulator comprising wheels provided with notched disks having stop shoulders adjacent the notches and crawl tens transfer gearing between said wheels, differential actuators including each a power element and primary and secondary elements complementally driven thereby, each primary element having operating connection with an accumulator wheel, and driving means adapted to operate all of the power elements simultaneously; of means cooperating with the accumulator, actuators and driving means to take a total, including a total key, totaling stops yieldably adjustable into the paths of movement of the stop shoulders, devices controlled by the total key and operable to adjust the totaling stops, and cooperating members controlled by the total key and operable upon interruption of said adjustment by engagement of any totaling stops with the peripheral faces of the related accumulator disk to move said primary elements to counteract partial tens transfers in the accumulator, and means including extensions of said members cooperating with said devices to lock the secondary actuator elements against operation by the driving means and each operable upon movement of the related totaling stop into the notch of its disk to release the secondary element.

6. In an adding machine having an accumulator comprising wheels provided with zero stops and crawl tens transfer gearing between said wheels, differential actuators for said wheels, and driving means for said actuators; means cooperating with the accumulator and actuators to take a total, including totaling stops adjustable into the paths of movement of the zero stops, cooperating members operable upon interruption of said adjustment by engagement of any totaling stops with the peripheral faces of the related zero stops to move the actuators to counter-act partial tens transfers in the accumulator, a total key, and means operable by said key independently of the drive means to adjust each totaling stop and its cooperating member seriatim to align the numeral wheels successively, from lower to higher order, said driving means being operable to move the actuators simultaneously to complete the movement of the wheels to zero.

7. In an adding machine having an accumulator comprising a series of wheels connected by crawl tens transfer gearing, and differential actuators each including a power element and primary and secondary elements complementally driven thereby and provided with normal position locators each primary element having operating connection with an accumulator wheel; snail cams each connected to an accumulator wheel, stops movable into contact with said cams, connections between each stop and the differential actuator and the secondary element, normal position locator of next higher order, and means for operating said connections independently of the power elements to disable said locators and impart to each differential actuator a movement limited by the lower order snail cam.

8. In an adding machine having an accumulator comprising a series of wheels connected by crawl tens transfer gearing, and differential actuators for said accumulator; snail cams each connected to an accumulator wheel, stops movable into contact with said cams, levers each engageable with a differential actuator, connections between each stop and the lever related to the differential

actuator of next higher order and including means for differentially operating the stops and levers, and means for operating said connections to impart to each differential actuator a movement limited by the lower order snail cam.

9. In an adding machine having an accumulator comprising a series of wheels connected by crawl tens transfer gearing, and differential actuators for said accumulator; snail cams each connected to an accumulator wheel, stops movable into contact with said cams, levers each engageable with a differential actuator, connections between each stop and the lever related to the differential actuator of next higher order and including means operable to cam the stops and levers differentially, and means for operating said connections to impart to each differential actuator a movement limited by the lower order snail cam.

10. In an adding machine having an accumulator comprising a series of wheels connected by crawl tens transfer gearing, and differential actuators for said accumulator; snail cams each connected to an accumulator wheel, stops movable into contact with said cams, levers each engageable with a differential actuator, connections between each stop and the lever related to the differential actuator of next higher order, operable to impart complementary movements to each stop and its related lever, and means for operating said connections successively to impart to actuators of successively higher order movements limited by the lower order snail cams.

11. In an adding machine, the combination with an accumulator comprising wheels provided with zero stops and crawl tens transfer gearing between said wheels, differential actuators including each a power element and primary and secondary elements complementally driven thereby and provided with normal position locators, each primary element having operating connection with an accumulator wheel, and driving means adapted to operate all of the power elements simultaneously; of means cooperating with the actuators and driving means to set the accumulator wheels to zero registering position, including stops adjustable into the paths of movement of the zero stops, and means operable to disable certain of the normal position locators to allow abnormal movement of the related actuator elements and to control the extent of movement of the secondary actuator elements.

12. In an adding machine, the combination with an accumulator comprising wheels provided with zero stops, differential actuators including each a power element and primary and secondary elements complementally driven thereby, each primary element having operating connection with an accumulator wheel, and driving means adapted to operate all of the power elements simultaneously; of means cooperating with the actuators and driving means to set the accumulator wheels to zero registering position, including actuator stopping devices comprising each a primary element adjustable into the path of movement of the related zero stop and a secondary element adjustable into the path of movement of the related secondary actuator element, and connections operable to adjust the primary and secondary stop elements complementally and to permit movement thereof in unison upon contact of the related zero stop with its primary stopping element.

GEORGE C. CHASE.
